SLEEPING DEVICE

Mario Lazo, Havana, Cuba

Application June 1, 1956, Serial No. 588,792

2 Claims. (Cl. 2—15)

This invention relates to a sleeping device and is more particularly concerned with a mechanical device for use in association with the eyes and adjacent parts of the human anatomy for the purpose of inducing or tending to induce a relaxed condition of the body, a condition favorable to sleep.

The present invention is to be distinguished from the customary eye shades or "sleep shades" which are substantially nothing more than excluders of light and which are provided mainly for persons who have difficulty in falling asleep in the presence of light, even very dim light, such as often results from diffusion of light from the exterior of a window around the sides of a window shade.

There are many persons who have difficulty in falling asleep irrespective of light conditions due to the fact that they have difficulty in relaxing. I have found that this condition can be ameliorated or completely overcome in many cases by the application of pressure to certain parts of the orbital region. In accordance with this invention, there is provided a device which can be removably attached to the head of a person in preparation for sleep. The device contains pressure applicator pads which are shaped and positioned so as to apply gentle pressure transmitted downwardly through the upper lid of the closed eyes against the eyeball and upwardly against the inferior aspect of the superior orbital rim or margin.

In the accompanying drawing there is illustrated an embodiment of this invention which will be more fully understood in conjunction with the following description.

In the drawing:

Figure 1 is a front elevation view of the device as it appears in operative position on the head of a person.

Figure 2 is a section along the line 2—2 of Figure 1.

Figure 3 is a rear perspective view of the device apart from the person.

Referring with more particularity to the drawing in which like numerals designate like parts, the embodiment illustrated comprises a sheet of relatively stiff material 11, such as a heavy cloth or cloth reinforced with buckram or crinoline 12, having a pair of lobe portions 13 and 14, one for each eye of a person, connected together by a somewhat narrower nose bridge portion 15. Elastic or non-elastic strings, cords or cloth 16 and 17 are attached to the outer ends of the device and to an adjustable elastic band 18 for encircling the head, as shown. The elastic band feature may be eliminated.

The inner side of the device (toward the face) is provided with two longitudinal oval-shaped pressure pad members 19 and 20, one in each of the lobes 13 and 14, respectively. The upper part of each lobe is adapted to lie against the forehead, just over the superior orbital rim of its corresponding orbital cavity, substantially as shown. The pad portions are oval in shape and disposed immediately below the superior orbital margin and are of generally triangular cross section to fit into the triangular space between the upper surface of the eyeball and the superior orbital margin. In this position, the inner sides 27 and 28 of these pad portions become slightly concave to fit the corresponding convex parts of the orbital cavity 25 and 26, respectively. And also, in this position, the pad exerts a gentle

2

pressure against both the eyeball and the roof of the upper orbital rim, the pressure being downward (against the eyeball) and upward against the orbital margin and adjacent roof, across which many nerves pass, as well as exerting a slight pressure inward against adjacent parts of the nose. The application of gentle pressure upon these areas is an essential feature of this invention. The magnitude of the pressure may be varied by adjusting the length of the band 18, if such a band is used.

10 The pad members 19 and 20 are secured permanently to the cloth material 11 by any suitable means, such as rows of stitches 29 and 30 around the margins. Part of the pad members could be left free so as to permit them to adjust themselves more readily to the anatomy of different faces. The pad itself may be made of any suitable material, such as fluffy cotton 31 enclosed in a light cloth casing 32.

15 The exclusion of light as a means of inducing sleep is well known and is not a factor of the present invention. It is, however, used in conjunction with it although the shade portion may be smaller in area (not reaching so far down on the cheek bones when in position) than is the case with the shades now commonly in use.

20 25 I have found that after using this device for a short time the two pressure pads 19 and 20 tend to adjust and fit themselves into the orbital cavities, a process which a person may aid by applying pressure by the elastic members 16 and 17 so as to pivot the two pressure parts into the orbital cavities. The upward pressure by the pad portions against the roof of the orbital cavity and inward toward the nose has a soothing and relaxing effect on the many nerves which crisscross the upper and inner area of the orbital regions of each eye.

30 35 Having thus described my invention, I claim:

1. A sleeping device comprising a sheet of material of a length to extend across the face of a person, said sheet having an upper portion adapted to rest against the forehead of the person over the eyebrows and having a lower edge adapted to rest over the cheek bones, a pair of oval-shaped pressure pads, one for each eye, carried by the sheet, each pad being substantially triangular in cross section, having its major axis in the horizontal direction and being secured to the inner side 40 45 of the sheet in a position opposite the cavity of the respective eye between the upper side of the eyeballs and the forehead and of a size to enter the said cavity exclusive of any other portion of the eyeball, and means for supporting the sheet on the face.

2. A sleeping device comprising a sheet of material of a length sufficient to extend across the face of a person and cover the eyes, said sheet being formed so that its upper edge is adapted to rest against the forehead of the person over the eyebrows and the lower edge over the cheek bones, a pair of oval-shaped pressure pads, one for each eye, said pads being substantially triangular in cross section, having their major axes in the horizontal direction, being attached to the inner side of the sheet and being of a shape, size and in a position on the sheet 50 55 to fit into the respective orbital cavity between the eyebrow and the upper part of the eyeball exclusive of any other portion of the eyeball and against the side of the nose ridge at the level of the eye, and means for supporting the sheet on the face.
